Des. 202,609
Patented Oct. 26, 1965

202,609

PUFFED SNACK FOOD PRODUCT

Verne E. Weiss, 14509 County Road 6, Minneapolis,
Minn., and Rolf Moen, 5235 Minnetoga Terrace, Hopkins, Minn.

Filed Oct. 1, 1964, Ser. No. 81,987

Term of patent 14 years

(Cl. D8—1)

FIG. 1

FIG. 2

FIG. 3

FIG. 4

We claim:

The ornamental design for a puffed snack food product, substantially as shown.
